UNITED STATES PATENT OFFICE.

BARTHolemew R. DOODY, OF CANTON, MASSACHUSETTS.

ACETYLENE-GAS GENERATOR.

SPECIFICATION forming part of Letters Patent No. 673,863, dated May 14, 1901.

Application filed December 26, 1900. Serial No. 41,055. (No model.)

To all whom it may concern:

Be it known that I, BARTHolemew R. DOODY, a citizen of the United States, residing at Canton, in the county of Norfolk and 5 State of Massachusetts, have invented a new and useful Machine to Generate Acetylene Gas from Calcium Carbid for Illuminating and other Purposes, of which the following is a specification.

10 My invention relates to improvements in acetylene-gas machines for the generation of acetylene gas; and the objects of my invention are, first, to enable the machine to be easily and safely charged with calcium carbid 15 without opening any part of the machine or interfering with its operation; second, to enable the residuum to be removed easily and safely without any loss of gas, without waste of water, and without opening any valve or 20 interfering with the operation of the machine, and, third, to automatically control the generation of gas. I attain these objects by the mechanism illustrated in the accompanying drawings, in which—

25 Figure 1 is a vertical section of the entire machine. Fig. 2 is a top view of the machine. Fig. 3 is a perspective view of holding-frame, calcium-carbid holder, and mechanism for operating said holder. Fig. 4 is a detail section of the calcium-carbid holder. Fig. 5 is a transverse section of Fig. 4, looking in the direction of the arrow.

Similar letters refer to similar parts throughout the several views.

30 A is a water-tank; B, a gas-bell; C, an automatic drip; D, a conduit from generator to gas-bell; E, a supply-pipe; F, an automatic blow-off; G, a generator; H, an opening in generator; I, walls of opening of generator; J, calcium-carbid holders; K, a calcium-carbid-holding frame; L, an operating-rod; M, calcium-carbid-holder supports; N, a set-screw for securing operating-rod; O, a handle of operating-rod; P, an arm with groove 35 a, in which pin b travels in tipping calcium-carbid holder; Q, sockets in calcium-carbid holder for receiving turned ends of calcium-carbid-holder supports M, upon which the calcium-carbid holder turns in tipping; R, a pin by which operating-rod is held and released; S, an arm or attachment to gas-bell for automatic operation of pin R, this arm being

provided with a tapering finger or projection S', adapted to enter the opening in the pin R to give the same a horizontal pull; T, a support for pin R; U, a drawer within calcium-carbid holder; V, a spring for holding drawer in holder; W, perforations in drawer; X, corrugations in drawer; Y, a hole in operating-rod to receive pin R; Z, water.

55 I would have it understood that any number of carbid holders and supports may be employed, and when a series are used the arm or attachment S is provided with a cross-head from which depend a series of the tapering fingers S', which are different lengths to form a succession of steps, so that one holder after the other is tilted when the gas-bell descends. This method has not been illustrated 60 in the drawings, but this change is warranted 65 without departing from the spirit of my invention.

70 The working of the machine is as follows: Calcium carbid is placed in the drawer U, which is then put into the calcium-carbid 75 holder J and held up within said holder a short distance from its open end by the spring V, as shown in Fig. 4. The holder is then by means of the operating-rod L put in a vertical position with its open end down and by 80 means of the set-screw N securely held in that position. Then by means of the calcium-carbid holding frame K, the operating-rod L, and the supports M the calcium-carbid holder J is plunged open end down through the opening H into the water, thus securing an air-cushion in the calcium-carbid holder J, which effectively prevents contact of water and carbid. The holder J is then pushed down 85 through the water by means of the holding-frame K and mechanism to the bottom of the generator G. The top of the holder J is then below the lower end of the wall I. Then the holding-frame K is turned so as to place the holder J directly under the space between the 90 inner wall I and the outer wall e of the generator. Then the holder J by means of the holding-frame K and mechanism described above is raised so as to bring the holder J between the inner wall I and the outer wall e 95 of the generator and above the lower end of the wall I, which wall is then between arm P and holding-frame K. The holding-frame is 100 then securely fastened to the generator by

means of the fastener *d*. The pin *R* is then inserted in hole *Y* and the set-screw *N* is released, allowing the operating-rod to be held solely by the pin *R*. As the gas-bell *B* descends the attachment *S* enters the opening *f* in the end of the pin *R* and drawing the pin *R* releases the operating-rod *L*, which being then without support falls by its own weight, and in falling the holder *J* is tipped from a vertical to a horizontal or inclined position by the arm *P*, groove *a*, and pin *b*, thus destroying the air-cushion which was retained in the holder *J* while in a vertical position and allowing the water to attack the carbid. 15 The residuum remains in the calcium-carbid holders *J* and is removed as follows: The calcium-carbid holder is brought back into a vertical position by operating-rod *L* and secured by set-screw *N*. The holding-frame *K* is then released from fastener, and the calcium-carbid holder is lowered by means of holding-frame and brought directly under opening *H* and then raised out of water. The drawer *U* is taken from calcium-carbid holder 25 and residuum removed.

What I claim as my invention, and desire to secure by Letters Patent, is—

1. The combination in an acetylene-gas machine, a generator, a water-tank, a gas-bell carried by the tank, supports mounted in said generator, tilting carbid-holders carried by said supports, and means carried by the gas-bell to automatically cause the holders to tilt and allow the carbid to be contacted by the 35 water in the generator.

2. The combination in an acetylene-gas machine, a generator having a cylindrical tube, supports depending into said generator and held in place by contact with the upper and 40 lower ends of said tube, tilting carbid-holders mounted in the lower ends of said supports, and means to cause said holders to tilt automatically.

3. The combination in an acetylene-gas machine, a generator, a water-tank having a gas-bell, and being in communication with said generator, supports movably secured and depending into said generator, tilting carbid-holders mounted in the lower ends of said supports, and means carried by the gas-bell to 45 automatically tilt said holders as described.

4. The combination in an acetylene-gas ma-

chine, a generator, a water-tank having a gas-bell, said generator and tank being in communication with each other, a support depending into said generator, a sliding sleeve mounted upon said support, a carbid-holder tiltingly mounted in the lower end of said support and connected with said sleeve, and means carried by the gas-bell to cause said sleeve to slide downwardly to tilt the carbid-holder as described. 55

5. The combination in an acetylene-gas machine, a generator, a water-tank having a gas-bell, and being in communication with said generator, a support depending into said generator, a sliding sleeve mounted upon said support, a carbid-holder tiltingly mounted in the lower end of said support and connected with the sleeve, a pin for holding the sliding 60 sleeve up, and means carried by the gas-bell to automatically release said pin, to allow said sleeve to slide downwardly to tilt the carbid-holder as described. 65

6. The combination in an acetylene-gas machine, a generator, a water-tank having a gas-bell, and being in communication with said generator, a support depending into said generator, a sliding sleeve mounted upon said support, a carbid-holder tiltingly mounted in the lower end of said support and connected with the sleeve, a pin to hold the sliding sleeve up, and an arm carried by said gas-bell, which when it descends causes the arm to engage said pin to allow the sleeve to slide downwardly to tilt the carbid-holder. 70

7. In combination with an acetylene-gas machine, of a carbid-holding device comprising a support, bearings or arms carried by the lower end of said support, a carbid-holder 75 tiltingly mounted in said bearings, a sliding sleeve mounted upon said support and connected to said holder, means to hold said sleeve up, and means to release said sliding means to allow the sleeve to fall and tilt the carbid-holder. 80

In testimony whereof I have signed my name to this specification in the presence of two subscribing witnesses.

BARTHOLOMEW R. DOODY.
